UNITED STATES PATENT OFFICE.

JOSEPH J. SZEPE, OF PITTSBURGH, PENNSYLVANIA, ASSIGNOR TO KEYSTONE DIE AND MANUFACTURING COMPANY, OF PITTSBURGH, PENNSYLVANIA, A CORPORATION OF PENNSYLVANIA.

TOY GUN.

1,403,719.

Specification of Letters Patent. Patented Jan. 17, 1922.

Application filed March 5, 1921. Serial No. 450,025.

To all whom it may concern:

Be it known that I, JOSEPH J. SZEPE, a citizen of the United States, residing at Pittsburgh, in the county of Allegheny and State of Pennsylvania, have invented new and useful Improvements in Toy Guns, of which the following is a specification.

My invention relates to toy guns.

The object of this invention is to provide a toy gun made principally from sheet metal and capable of being readily assembled and cheaply manufactured. It is also the object to provide a toy gun with a magazine for projectiles, such as shot, and with a trigger so connected with certain spring-operated propelling means for the projectiles that the entire magazine can be exhausted by simply operating the trigger repeatedly. Other objects appear hereinafter.

Referring to the accompanying drawings, Fig. 1 is a perspective view of my improved toy gun; Fig. 2, a central vertical longitudinal section of the same with some parts in elevation and others broken away; and Fig. 25, a top plan view with the cover omitted.

I provide a casing 1 composed of sheet-metal. The sides 2 of the casing are bent up at right angles with the bottom 3 and converge at the upper portion. The front and rear edges of the sides have the ears or tongues 4 which extend through the front and rear ends 5 and 6 of the casing and are bent down against the outer faces of the said ends. The upper edges of the sides 2 have the outwardly-turned flanges 7. The cover 8 has its side edges provided with inwardly-turned flanges 9 which receive the flanges 7 to hold the cover in place and guide it when moved longitudinally.

The plate 10 lies on the lower face of the bottom 3 and has the ears 11 extending up through the bottom 3 and through the middle member 12 of the U-shaped support 13, the member 12 lying on the upper face of the bottom and secured to the bottom by the said tongues which are bent down on the upper face of the member 12. The plate 10 has the depending ears 14 seated between the upstanding ears 15 on the upper swivel plate 16. A pivot pin 17 extends through both pairs of ears 14 and 15 so that the casing may be rocked vertically. The lower swivel plate 18 is connected to the upper swivel plate 16 by the vertical pivot 19 so that the

casing may be swung horizontally. The 55 plate 18 is supported by three sheet-metal legs 20, each ribbed lengthwise at 21 and transversely at 22. The upper ends of the legs have each a tongue extending through the plate 18 and turned down on the upper 60 face thereof. The upper ends of the ribs 21 serve to limit the outward movement of the legs, and form a rest for the plate 18, and stiffen the legs. A triangular brace plate 23 has its corners seated in the transverse ribs 65 22, the corners having ears or tongues 24 extending through the legs and turned up against their outer faces.

The support 13 has the two upstanding members 25 and 26, the latter having a vertical slot 27 and the former a vertical slot 28 in horizontal alinement with the slot 27. The plunger tube or gun-barrel 29, having the hole 63 in its upper side, is secured in a hole in the member 25 above the slot 28 75 and extends out through the front 5 a short distance, the front 5 and the member 25 holding the barrel 29 rigidly in place. The upper end of the member 25 is bent forwardly slightly above the tube 29 and then 80 rearwardly, thereby forming the guide members 30 and 31 spaced apart to receive the projectile-feeding member 32, provided with a vertical opening 33 adapted to register with the vertical holes 34 and 35 in 85 the members 30 and 31.

36 is a plunger reciprocable in the inner end of the gun barrel and having the shoulder 37 on its lower side facing the front of the gun. The rear end of the plunger 90 is flattened and extends through the rear end 6 and is provided with the upturned lug 38 engageable with the rear face of the end 6 to limit the forward movement of the plunger. A spring 39 tends to hold the 95 plunger in its normal position as shown on Fig. 2 and to return it to such position when displaced therefrom. At the junction of the members 30 and 31 there is a horizontal slot 40 for the front end of the feeder 32. 100

41 is a bar slidabie in the slots 27 and 28 and a slot 42 in the rear end 6 of the casing. The forward end of the bar 41 carries the trip or tripping member 43, pivoted between its ends on the horizontal pin 44, the front 105 end of the member 43 being the heavier and provided with the downwardly-extending lug or trip 45 which is adapted to engage

with the lower end of the slot 28 and rock the forward end of the member 43 downwardly out of engagement with the shoulder 37, when the bar 41 has been drawn rearwardly a certain distance.

46 is a handle made up of two lateral members 47 of sheet-metal having abutting inturned flanges 48, the members being secured together by rivets 49, the forward one 10 of which is pivoted to the trigger 50 extending through the slot 51 in the lower side of the handle. The spring 52 tends to move the trigger forwardly. The rear end of the bar 41 has the hook 53 extending 15 through a hole 54 in the trigger and interlocked with the metal at the lower end of the hole. The forward end of the handle has the ears or tongues 55 which extend through the rear end 6 and are clinched 20 down against the inner face of the same.

The tube or false barrel 56 is arranged concentric with the barrel 29 and has its rear end provided with the ears or tongues 57 which extend through the front 5 and 25 are clinched down against the inner face thereof.

I provide a piece of sheet-metal bent at its middle to form the bottom and rear walls 58 and 59 of the projectile magazine 30 60 whose other walls are portions of the sides 2 and the front 5. The wall 59 has the ears or tongues 61 extending through the sides 2 and bent down against the outer 35 faces thereof. The member 58 has a vertical hole registering with the holes 34 and 35 in the guide members 30 and 31. The magazine 60 contains the projectiles 62, such as BB shot.

When the parts are as shown on the 40 drawings, the hole in the bottom of the magazine, the holes 34 and 35, the hole 33 in the feeder 32, and the hole 63 in the upper side of the gun barrel 29 are all in vertical registry with one another, the plunger 45 36 having its forward end somewhat in front of the opening 63. A projectile 62 drops through all the said holes except the holes 33 and 35 in which the projectile comes to rest on the plunger, the top of the projectile being just below the feeder 32. The trigger is drawn rearwardly, causing the bar 41 and the trip 43 to move with it. The rear 50 end of the trip, by engagement with the shoulder 37, causes the plunger 36 to be drawn rearwardly against the tension of the spring 39. The feeder plate 32 moves rearwardly presenting an unperforated portion 55 thereof between the projectile on the plunger and the remainder of the projectiles above. At about the time when the plunger is withdrawn from below the hole 63 in the barrel 29, the lug 45 on the trip, by engagement 60 with the bottom of the slot 28, has moved the trip out of engagement with the shoulder, whereupon the projectile on the plunger

drops down in front of it and the spring 39 pushes the plunger suddenly forward, causing the plunger to expel the projectile from the barrels 29 and 56. When this has been accomplished, the parts are again in 70 the original position, at which another projectile 62 will drop down on the plunger 36, as shown on Fig. 2. By means of the pivots 17 and 19, the gun can be moved laterally and vertically in order to aim it at 75 a suitably arranged target.

I do not desire to be restricted to the precise elements and combinations shown and described, but desire to cover such combinations and arrangements of the said elements as may come within the scope of the appended claims.

I claim:

1. In a toy gun, a barrel therein having an opening for the deposit of a projectile in the barrel, a plunger reciprocable across the opening to prevent a projectile resting against it from dropping into the barrel and movable past the opening to allow the projectile to drop into the barrel, means for so moving the plunger, means tending to return the plunger forcibly to its normal position, means disconnecting the plunger and its moving means after the plunger has passed the said opening, a projectile magazine having means for feeding projectiles to the barrel, and a device for cutting off the feed of projectiles to the barrel when the plunger has uncovered the said barrel opening. 100

2. In a toy gun, a barrel therein having an opening for the deposit of a projectile in the barrel, a plunger reciprocable across the opening to prevent a projectile resting against it from dropping into the barrel and movable past the opening to allow the projectile to drop into the barrel, a pivoted trip, means for moving the same lineally, a shoulder on the plunger and in the path of the trip, stationary means for moving the trip to release the plunger when the plunger has passed the said opening, and means for forcibly returning the plunger when released and for automatically resetting the trip. 115

3. In a toy gun, a barrel therein having an opening for the deposit of a projectile in the barrel, a plunger reciprocable across the opening to prevent a projectile resting against it from dropping into the barrel and movable past the opening to allow the projectile to drop into the barrel, a pivoted trip, means for moving the same lineally, a shoulder on the plunger and in the path of the trip, a lug on the trip, stationary means for engaging the lug and thereby moving the trip to free the plunger when it has passed the said opening, and means for forcibly returning the plunger when released. 130

4. In a toy gun, a barrel, a plunger reciprocable therein, and having a shoulder thereon, a bar parallel with the plunger, a trip pivoted between its ends and carried by the bar 5 and having a portion at one side of its pivot arranged to engage said shoulder and move the plunger, stationary means for engaging a portion upon the other side of the pivot of the trip to release the same from 10 the shoulder when the plunger has been moved a predetermined distance, and means for forcibly returning the plunger to its normal position when so released.

5. In a toy gun, a barrel having an opening 15 in its side, a plunger reciprocable therein past the opening, a member supporting a portion of the barrel and reversely bent above the barrel to form spaced guide members, there being holes in the members 20 in alinement with the opening in the barrel, a projectile cut-off guided between the members and having a hole adapted to be in alinement with the said holes, but to be moved out of such alinement when the 25 plunger uncovers the said opening, and a magazine for feeding projectiles to said opening.

6. In a toy gun, a barrel having an opening 30 in its side, a plunger reciprocable therein past the opening, a member supporting a portion of the barrel and reversely bent above the barrel to form spaced guide members, there being holes in the members 35 in alinement with the opening in the barrel, a projectile cut-off guided between the members and having a hole adapted to be in alinement with the said holes, but to be moved out of such alinement when the plunger uncovers the said opening, a magazine 40 for feeding projectiles to said opening, a bar reciprocable in a slot in the said member below the barrel, a trip carried by the bar and engageable with the plunger, and

means on the trip for releasing the trip from the plunger.

7. In a toy gun, a sheet-metal casing comprising a bottom, two side members bent up therefrom, end members, tongues projecting from one member through the other member and clinched against the latter, a 50 projectile magazine having its bottom and rear side connected to the casings by clinched tongues, a barrel in the casing and having a projectile receiving opening, and means to control the feed of projectiles to 55 the barrel, a part of such means comprising a plunger reciprocable in the barrel past the opening.

8. In a toy gun, a casing, a barrel therein, a plate resting on the bottom of the casing 60 and having an upstanding member supporting the barrel, a plate resting on the lower face of the casing and having pivot bearings, one of the plates having tongues extending through the bottom of the casing and through 65 the other plate and clinched upon the latter, a horizontal pivot extending through the pivot bearings, and a means for supporting the second plate.

9. In a toy gun, a casing, a barrel therein, 70 a plate resting on the bottom of the casing and having an upstanding member supporting the barrel, a plate resting on the lower face of the casing and having pivot bearings, one of the plates having tongues extending 75 through the bottom of the casing and through the other plate and clinched upon the latter, a horizontal pivot extending through the pivot bearings, a means for supporting the second plate, and a vertical 80 pivot connecting parts of the last means, whereby the casing may have universal movement.

Signed at Pittsburgh, Pa., this 1st day of March, 1921.

JOSEPH J. SZEPE.
